The ornamental design for a sound concentrating and directing horn attachment for loudspeakers, as shown and described.

DESCRIPTION

FIG. 1 is a perspective view of a sound concentrating and directing horn attachment for loudspeakers, showing my new design;

FIG. 2 is a front elevational view thereof;

FIG. 3 is a right side elevational view thereof;

FIG. 4 is a perspective view of a second embodiment of the design in FIG. 1;

FIG. 5 is a front elevational view thereof;

FIG. 6 is a right side elevational view thereof;

FIG. 7 is a perspective view of a third embodiment of the design in FIG. 1;

FIG. 8 is a front elevational view thereof; and,

FIG. 9 is a left side elevational view thereof.

FIG. 1

FIG. 2

FIG. 3

FIG. 4

FIG. 5

FIG. 6

FIG. 7

FIG. 8

FIG. 9
